CORNELIUS G. WEBER, OF MILWAUKEE, WISCONSIN

HEAT-ACTUATED DEVICE

Application filed January 12, 1928. Serial No. 246,284.

This invention relates to improvements in heat actuated devices.

Various types of heat actuated devices have been in use heretofore for opening valves or for imparting motion to some form of mechanism when a predetermined temperature is reached in the locality of the device. One type, which makes use of a fusible link, is open to the objection that it is affected alike by a gradual or by a sudden rise in temperature. Furthermore, when the fusible link is used in automatic sprinkler systems, a separate link has to be provided for each nozzle in the system. Another type of device comprises a single container filled with an expansible fluid. The container is connected by tubing to an expansible member which moves the actuating mechanism when the fluid pressure, due to a rise in temperature, affects the expansible member. In this type of device a vent is used in the tube which vent is so restricted that the fluid can escape only very gradually. Thus, upon a slow rise in temperature, the fluid will escape through the vent without affecting the expansible member. However, upon a sudden rise, the expanding fluid will not have time to escape and will pass the vent and operate the expansible member. Thus the device will operate only when a rapid rise in temperature, such as that caused by a fire, takes place. This device, however, is open to the objection that the vent is not possessed of constant characteristics, as moisture or dust may either stop up the vent entirely, or else change the rate at which the fluid can pass therethrough.

It is one of the objects of the present invention to overcome the aforementioned objections, and to provide a heat actuated device, which may be used to control mechanism generally, but which is more particularly adapted for use in automatic sprinkler systems, which operates only upon a rapid rate of rise in temperature, that is, when the temperature rises at a predetermined minimum rate, and which device has no air vent in which foreign matter can accumulate to cause a stoppage.

It is a further object of this invention to provide a heat actuated device, which, when

used in an automatic sprinkler system, controls the main valve or other valves, and operates all of the sprinkler nozzles simultaneously, without the necessity of having a separate control for each nozzle.

It is a more specific object of this invention to provide a heat actuated device having two containers with an expansible fluid therein, the contents of only one of said containers being affected for a time period by a rapid change in temperature, said fluid operating to actuate a valve or other mechanism, whereas the fluids in both containers will be affected by a gradual change in temperature and as the force created by the fluid in one container operates in a direction opposed to the force created by the fluid in the other container, they will equalize one another, and the actuating mechanism will not be put into operation.

It is a further object of this invention to provide a heat actuated device which is simple in construction and operation, and well adapted for the purpose described.

With the above and other objects in view, the invention consists of the improved heat actuated device and all its parts and combinations as set forth in the claims and all equivalents thereof.

In the accompanying drawing, in which the same reference characters designate the same parts in all of the views:

Fig. 1 is a view of a portion of a sprinkler system equipped with the improved heat actuated device;

Fig. 2 is a similar view on an enlarged scale showing the heat actuated mechanism, in detail, parts being broken away, and parts being shown in section; and

Fig. 3 is a sectional view taken on line 3—3 of Fig. 2.

Referring to the drawing, the numeral 5 designates an outer container or thermostatic member, constructed preferably of metal. Within the container 5 is a second container 6, maintained in position in the outer container by supports 7, said inner container having an opening 8 therein. A tube 9 is connected to the outer container, and a tube 10 directly communicates with the opening 8.

of the inner container. The inner container may be covered with any insulating material if desired to prevent the fluid within from being susceptible to rapid changes in temperature. If desired, the containers may be separate, but it may be more convenient and effective in some cases to have one positioned within the other as shown. Any number of intermediate containers may be used, and in 10 sprinkler systems they may be positioned at intervals throughout a building as shown in Fig. 1.

The tube 9 is connected to one end of a bellows-like member or diaphragm or other 15 expansible member 11 and the tube 10 to one end of a similar expansible member 12. The other ends of the expansible members are connected together by a rod 13. The containers, tubes, and expansible members are 20 filled with a fluid such as gas, air, or some volatile fluid which readily expands or contracts according to temperature changes. It may readily be seen that upon expansion of the fluid in the outer container for a predetermined period only, a pressure due to the 25 time lag of the heating of the fluid in the inner cylinder, is created within the member 11, causing the same to expand and move the rod 13 to the left. When, on the other hand, 30 the fluid in both containers expands substantially equally, there will be two substantially equal and opposite forces working on the rod 13, which will equalize each other, and as a result the rod will remain practically stationary.

A lug 14 is secured to the rod 13 by a set screw 15. Below the rod 13 is a rod 16 journaled in suitable bearings 17. An extension arm 18 is rigidly secured to the rod 16, and 40 normally is engaged by the lug 14 on the rod 13. A lever 19, also rigidly secured to and extending from the rod 16, has extending therefrom a cord 20, on the lower end of which is a weight 21. A lug 22 is also secured 45 to the rod 16 normally engaging one end 23 of a bell crank lever. The bell crank lever is mounted on the rod 24. The other end 25 of the bell crank lever has a cord 26 extending therefrom, on the lower end of which is a 50 weight 27. The end 25 of the bell crank lever engages a valve lever 28 on the valve 29 of a water supply pipe 30. The supply pipe is in connection with other pipes 31, on which nozzles 32 are positioned at intervals.

55 The operation of the device is as follows: When the temperature in the region of the container rises at a rate greater than a predetermined minimum, as when a fire occurs, the fluid in the outer container 5 expands. 60 The fluid in the inner container will not be affected as rapidly, due to the fact that it is spaced or insulated from the outer container. As a result there will be a fluid pressure transmitted through the tube 9 to the 65 expansible member 11, and the latter will ex-

pand, moving the rod 13 lengthwise so that the lug 14 will disengage the extension arm 18. The pressure in the expansible member 12 will be almost negligible as there has been insufficient time for the increased temperature to penetrate the inner container 6, and as a result the fluid within the latter has been unaffected. As the member 18 has been disengaged by the lug 14, the weight 21 will cause the rod 16 to rotate. This will in turn cause the lug 22 to disengage the lever end 23, allowing the weight 27 to pull down on the lever end 25 causing the latter to move the valve lever 28 to open the valve. This permits water to circulate through the pipes 80 31, and out of the nozzles 32 to extinguish the fire. When there is a gradual rise in temperature such as is caused by ordinary changes in temperature conditions, there will be ample time for the heat to penetrate the 85 covering of the inner container and as a result, the fluid in both containers will be affected substantially alike by slow temperature changes. As both fluids will exert a pressure there will be opposite forces working 90 on each end of the rod 13, and as a result, they will substantially equalize one another and no movement of the rod 13 will occur. Thus the actuating mechanism will not be put into operation by slow temperature 95 changes, but only by rapid changes such as are caused by a fire.

Although the device has been described with reference to its use in automatic 100 sprinkler systems, it is not desired to limit the scope of this invention to that particular adaptation, as the broad concept contemplates other uses such as the starting and stopping of motors, and the opening and closing of doors, windows, or valves of various types. Furthermore, the device does not necessarily 105 have to operate through mechanical means, but it may be used to operate electrical controls which will put into operation mechanism for opening or closing valves or other 110 mechanism.

From the foregoing description it may be seen that the improved heat actuated device 115 is simple in construction and operation, and well adapted for the purpose described.

What I claim is:

1. A heat actuated device comprising actuating mechanism, means normally engaging said actuating mechanism to hold the same in inoperative position, thermostatic means rapidly influenced by rapid changes in temperature for controlling said engaging means, and a second thermostatic means affected less rapidly than the first mentioned thermostatic means by rapid changes in temperature, but affected the same in substantially the same length of time by slow temperature changes for preventing the first mentioned thermostatic means from operating the en- 120 125 130

gaging means when a slow temperature change occurs.

2. A heat actuated device comprising actuating mechanism, means normally engaging said actuating mechanism to hold the same in inoperative position, an expansible member connected to each end of and operating towards each other upon said engaging means for operating said engaging means to release said actuating mechanism, a container in communication with each of said expansible members, and an expansible fluid in each container and each expansible member, the fluid in each container being in communication with the fluid in its respective expansible member, the relative arrangement of said containers being such that one of said fluids is more rapidly influenced by a rapid change in temperature in the region of the containers than the other.

3. A heat actuated device comprising actuating mechanism, means normally engaging said actuating mechanism, to hold the same in inoperative position, an expansible member connected to each end of and operating towards each other upon said engaging means for operating said engaging means to release said actuating mechanism, an outer container in communication with one of said expansible members, a second container positioned within said outer container and having a tubular connection with the other expansible member, and an expansible fluid for each container, the fluid in the outer container being more rapidly influenced by a rapid change in temperature in the region of the containers than the fluid in the other.

4. A heat actuated device comprising actuating mechanism, means normally engaging said actuating mechanism to hold the same in inoperative position, an expansible member connected to each end of and operating towards each other upon said engaging means for operating said engaging means to release said actuating mechanism, an outer container, a second container positioned within said outer container, a tubular member connecting each container with its respective expansible member, and an expansible fluid for each container, the fluid in the outer container being more rapidly influenced by a rapid change in temperature in the region of the containers than the fluid in the inner container.

5. A heat actuating device comprising a control member, weight means for operating said control member, engaging means normally holding the weight means in inoperative position, and thermostatic means so arranged as to cause actuation of the engaging means only when a rapid change in temperature in the region of the thermostatic means occurs.

6. A heat actuated device comprising a control member, a lever for operating said

control member, a weight for operating said lever, engaging means for said lever for normally holding it in inoperative position, a weight for operating said engaging means, a second engaging means for holding said second weight in inoperative position, and thermostatic means so arranged as to cause actuation of said second engaging means only when a rapid change in temperature in the region of the thermostatic means occurs.

7. The combination with a sprinkler system having a control valve, of actuating mechanism for said valve, means normally engaging said actuating mechanism to hold the same in inoperative position, thermostatic means rapidly influenced by rapid temperature changes for controlling said engaging means, and a second thermostatic means affected less rapidly than the first mentioned thermostatic means by rapid temperature changes, but affected the same in substantially the same length of time by slow temperature changes for preventing the first mentioned thermostatic means from operating the engaging means when a slow temperature change occurs.

8. The combination with a sprinkler system having a control valve for a plurality of nozzles, of actuating mechanism for said valve, means normally engaging said actuating mechanism to hold the same in inoperative position, a thermostatic member, portions of which are remotely positioned, said remotely positioned portions being affected rapidly by rapid temperature changes for controlling said engaging means, and a thermostatic member, portions of which are also remotely positioned, said remotely positioned portions being affected less rapidly by rapid temperature changes, but being affected the same in substantially the same length of time by slow temperature changes for preventing the first mentioned thermostatic means from operating the engaging means when a slow temperature change occurs.

9. A heat actuated device comprising actuating mechanism, thermostatic means rapidly influenced by rapid changes in temperature for controlling said actuating mechanism, and a second thermostatic means affected less rapidly than the first mentioned thermostatic means by rapid changes in temperature, but affected the same in substantially the same length of time by slow temperature changes for preventing the first mentioned thermostatic means from operating the actuating mechanism when a slow temperature change occurs.

10. A heat actuated device comprising actuating mechanism, means normally engaging said actuating mechanism to hold the same in inoperative position, an expansible member connected to each end of and operating towards each other upon said engaging means for operating said engaging means to

release said actuating mechanism, and a container holding an expansible fluid in communication with each of said expansible members, the relative arrangement of said containers being such that the fluid in one of said containers is more rapidly influenced by a rapid change in temperature in the region of the containers than the other.

In testimony whereof, I affix my signature.
